(57) **CLAIM**

The ornamental design for a compact cordless motorized shade or screen, as shown and described.

DESCRIPTION

FIG. 1 is a front view of a compact cordless motorized shade or screen showing the new design.

FIG. 2 is a rear view of FIG. 1.

FIG. 3 is a top view of FIG. 1.

FIG. 4 is a bottom view of FIG. 1.

FIG. 5 is a first side view of FIG. 1.

FIG. 6 is a second side view of FIG. 1.

FIG. 7 is a top perspective view of FIG. 1.

FIG. 8 is a bottom perspective view of FIG. 1.

FIG. 9 is an enlarged front view of one end cap of the compact cordless motorized shade or screen of FIG. 1, shown separately to show aspects of the design that may not be apparent in the other views.

FIG. 10 is a back view of the end cap shown in FIG. 9.

FIG. 11 is a top view of the end cap shown in FIG. 9.

FIG. 12 is a bottom view of the end cap shown in FIG. 9.

FIG. 13 is a first side view of the end cap shown in FIG. 9.

FIG. 14 is a second side view of the end cap shown in FIG. 9.

FIG. 15 is a first perspective view of the end cap shown in FIG. 9.

FIG. 16 is a second perspective view of the end cap shown in FIG. 9.

FIG. 17 is an enlarged front of the other end cap of the compact cordless motorized shade or screen of FIG. 1, shown separately to show aspects of the design that may not be apparent in the other views.

FIG. 18 is a back view of the end cap shown in FIG. 17.

FIG. 19 is a top view of the end cap shown in FIG. 17.

FIG. 20 is a bottom view of the end cap shown in FIG. 17.

FIG. 21 is a first side view of the end cap shown in FIG. 17.

FIG. 22 is a second side view of the end cap shown in FIG. 17.

FIG. 23 is a first perspective view of the end cap shown in FIG. 17; and,

FIG. 24 is a second perspective view of the end cap shown in FIG. 17.

The broken lines shown in the drawings depict environmental subject matter only and form no part of the claimed design.
